VALVE FOR ROCK DRILLS

Henry O. Fossum, Detroit, Mich., assignor to
Chicago Pneumatic Tool Company, New York,
N. Y., a corporation of New Jersey

Application February 23, 1944, Serial No. 523,523

1 Claim. (Cl. 121—19)

1
This invention relates to rock drills and more particularly to automatically operated distributing valves for rock drills of the fluid driven percussive type.

The main object of the invention is to provide a positively and automatically actuated distributing valve which, together with cooperating valve seats and motive fluid ports and passages, is of such efficient design and arrangement that the motive fluid will flow with substantially full power from the fluid source to the piston for highly effective operation of the latter.

It is therefore an important object of this invention to arrange the distributing valve and its associated seats and fluid ports to produce substantially a streamlined flow of the motive fluid to the hammer piston.

Another object is to have a distributing valve provided with opposite holding faces and characterized by the fact that after being tripped in either direction, the face which, prior to the tripping operation, acted as a holding area ceases to function as such and the opposite face becomes a holding area.

A further object is to provide a valve of the kind indicated for controlling automatically not only the movements of the piston but also for controlling an auxiliary exhaust means for the forward cylinder chamber in front of the piston to increase the power of the forward stroke of the latter.

Other objects and the advantages inherent in the nature and the construction of the invention and resulting from its practical application in the art will become apparent as this specification proceeds.

In the accompanying drawings:

Fig. 1 is a fragmentary longitudinal section of a rock drill including a distributing valve embodying the invention in practical form, the valve and a working piston controlled thereby being shown in initial rearward operative positions;

Fig. 2 is a similar view showing the valve and piston in fully operated forward positions preparatory to return thereof to original positions;

Fig. 3 is a similar section to that of Fig. 1 but showing a modification of the valve and its associated parts, the valve and piston occupying rearward initial operative positions as in said Fig. 1; and

Fig. 4 illustrates the same modification as in Fig. 3 with the valve and piston in extreme forward operated positions as in Fig. 2.

Throughout the views the same references indicate the same or like parts.

2
In fluid actuated rock drills, the intensity of the blow delivered by the piston or striking element of such a drill is largely influenced by the ease of flow of the motive fluid through the channels or passages controlled by the distributing valve thereof during the forward or working stroke of the piston. It is important that the motive fluid passages be as free as possible from irregularities, abrupt or indirect constrictions or sharp bends so as to provide a streamlined flow or at least straight line travel from fluid source to the piston. It is thus obvious that introduction of tortuous or sharp bends resulting from the construction of the distributing valve shall also be avoided to the same end.

Hence, referring again to the drawings, in the practice of the invention a rock drill casing, generally indicated at 10 contains a hammer piston 11 reciprocable within a cylinder 12 divided into a rear cylinder chamber 13 and a forward cylinder chamber 14 by means of an intermediate located annular exhaust groove or channel 15 communicating with the atmosphere through a main exhaust opening or port 16. The forward portion or shank 17 of the piston is fluted at 18 and guided in a front cylinder washer 19 which forms a fixed part of the casing 10. The washer also provides a closure for the front end of forward cylinder chamber 14, while the rear end of the cylinder chamber 13 is closed by a valve cap 20 seated against a shoulder 21 in a counterbore 22 in the casing. Valve cap 20 is provided with a plurality of fluid inlet passages or ports 23, 23 for supplying motive fluid directly against the rear end or face 24 of piston 11, as will presently be explained. Located rearwardly of said valve cap in the same counterbore 22 is a valve block 25, beyond which is located a ratchet ring 26 of conventional type surrounding a plurality of pawls (not shown) carried by a rifle bar 27 associated with the hammer piston to rotate the latter. A back head 28 completes the end closure of casing 10 and confines the ratchet ring 26 in place between the back head and the casing, said back head being secured to the latter by the usual through bolts (not shown).

Within the valve cap 20 and valve block 25 is mounted the fixed bushing 29 virtually suspended by the ends thereof, with one end secured in the valve cap and the other end secured in the rear portion of the valve block. The bushing has a pair of separate locating flanges 30, 31 respectively engaging against inwardly extending flanges 32 and 33 of said valve cap and valve block serving to retain the bushing in place. The for-

ward end 34 of the valve block is fitted upon the rearward projection 35 of the valve cap against shoulder 36 thereof, with the result that said valve cap 20, valve block 25, and bushing 29 together form a valve casing or chest for a hollow reciprocable distributing valve 37 surrounding the fixed bushing 29 generally without contact therewith and mounted for longitudinal sliding movement within said valve cap and valve block.

In order to supply motive fluid to the distributing valve, the throttle valve 38 is rotatably mounted in back head 28 and controlled by hand lever 39, while the interior chamber 40 thereof is connected to a continuous supply of motive fluid under pressure (not shown). When the throttle valve is open, as illustrated, the motive fluid passes through passage 41 to chamber or reservoir 42 in the back head and thence through passages 43 within the ratchet ring 26 to fluid reservoir 44 in valve block 25. From this reservoir the fluid travels onward through several inlet ports 45 in block 25 to the annular passage 46 about bushing 29 and within the hollow valve 37. Bushing 29 extends throughout the interior of the distributing valve and the position of the latter valve with respect to the bushing determines the further course of the fluid. When the distributing valve and the piston occupy the rearward or initial operative position shown in Fig. 1, the motive fluid travels forwardly beneath an internal or inwardly directed flange 47 within distributing valve 37, over the shoulder formed by retaining flange 30, past the forward end 48 of the valve, into an annular distributing passage or groove 49 and thereafter escapes through the fluid inlet ports 23, 23 opening therefrom into the rear cylinder chamber 13, where the force of the fluid is exerted against the rear face 24 of piston 11 to drive the same forward to the extreme operated position illustrated in Fig. 2.

However, during the forward travel of the piston, and approximately at the position indicated by broken line 50 (Fig. 2), said piston uncovers port 51 in the cylinder wall above the piston, communicating through control valve 52 with fluid return flow passage 53 which in turn communicates with annular valve flange chamber 54, allowing the motive fluid in the rear cylinder chamber 13 suddenly to rush into annular chamber 54 as indicated by the broken arrows in Fig. 2, and immediately exert pressure on the rear surface 55 of the valve shoulder or flange 56 tending to overcome the active fluid pressure on the forward end 48 of the valve as well as on the forward face 57 of internal flange 47 and thereby tend to displace the valve 37 forwardly into the position shown in said Fig. 2. Prior to such movement of the valve, the motive fluid impinges at high velocity against the rear face 58 of internal flange 47, and in passing forward between the latter and the shoulder 59 on bushing 29 toward ports 23, tends to produce a partial vacuum on front face 57 of the flange and thus assists in shifting the valve forward. In the attained forward position of the valve, the end 48 thereof overlies shoulder or flange 30 of bushing 29 in contact with the periphery thereof and cuts off further supply of fluid to rear cylinder chamber 13.

In fact, an important feature of the invention is the arrangement of the internal flange 47 on the distributing valve 37 in a position to surround the shoulder 59 upon bushing 29 which increases the diameter of the latter ad-

jacent to the flange and renders the flange particularly responsive to changes in the velocity of the pressure fluid travelling forward within the valve through the annular passage 46 from reservoir 44. The flow of the pressure fluid between the bushing and said internal flange 47 is obviously somewhat restricted by the increase in the diameter of the bushing occasioned by the presence of shoulder 59. Hence, as already indicated, the velocity of the motive fluid flowing past the internal flange creates a partial vacuum beyond the flange which, with the pressure of the motive fluid impinging on rear flange face 58 tends suddenly to shift the valve forwardly despite counter pressures due to the effect of the differential areas upon the forward and rear faces of the valve and its flanges, while in similar fashion rearward shifting of the valve is likewise facilitated. When the valve is in its forward position, the internal flange 47 tends to shift it rearwardly due to the greater area at its front face 57 than at its rear face 58, both faces then being under the same static pressure per unit area. On the other hand, when the valve is in its rearward position (Fig. 1) the internal flange tends to shift it forward due to the preponderance of dynamic force on rear face 58 as compared with the reduced pressure against front face 57 and in spite of the smaller area of the rear face. The flange 47 thus assists in the tripping of the valve 37 in both directions, resulting in a quicker, more positive, valve action, greater power and a reduction in air consumption.

It is, of course, understood that the stroke of the piston is very swift, so that the portion of the movement of the piston occurring from the point indicated by the broken line 60 to that indicated by line 50 while uncovering port 51 is substantially instantaneous, and shortly thereafter, when the valve 37 has been shifted so as to cut off the motive fluid, the piston has attained the final operated position and uncovered the annular exhaust groove 15 for release of the compressed fluid from cylinder chamber 13 through exhaust port 16.

At this juncture it may be mentioned that prompt or even abrupt shifting of valve 37 in the forward direction is facilitated by the presence of a fluid clearance or breather port 61 exposing the forward face 62 of valve flange 56 to the atmosphere to prevent entrapment of air and building up of an air cushion in front of the valve. In somewhat similar fashion, the rear fluid clearance or bleeder port 63 is provided for clearing out excess pressure fluid from passage 53 and flange chamber 54 during part of the rearward or return stroke of the piston as will immediately appear.

When the distributing valve has been displaced forwardly to occupy the position shown in Fig. 2 as already described, shoulder portion 64 which includes a reduced portion upon the rear of the valve 37 clears the inner edge of the rear face 65 of the annular groove or port 66 in valve block 25 surrounding the valve, so that the motive fluid arriving through ports 45 from reservoir 44 will proceed between said valve shoulder portion and the edge of face 65 into said annular groove 66. As the latter connects with the piston return passage 67 which in turn opens into the forward cylinder chamber 14 through a port 68, the motive fluid will immediately exert its pressure against the effective front working face

69 of the piston and drive the same rearwardly again to the starting position of Fig. 1.

During the initial part of the return stroke when the rear end of the piston has again covered the annular exhaust groove 15 and is travelling from the rear edge of said groove 15 to approximately the position indicated by broken line 60 (Fig. 2), the piston covers the port 51 above it while partly compressing the fluid in rear cylinder chamber 13, initially communicating the pressure thus produced to said port 51 and passage 53. After the piston has covered port 51 during such rearward movement, further communication between the latter and the rising pressure in the cylinder chamber is cut off, but as port 51 and the passage 53 are connected to the flange chamber 54 which is vented to the atmosphere by rear bleeder port 63 the fluid in said passage will in great part escape through the latter so as to clear pressure fluid from behind valve flange 56 preparatory to rearward shifting of valve 37. When the forward end 69 of the piston has uncovered the annular exhaust groove 15 so as to release the pressure fluid in front cylinder chamber 14 through exhaust opening 16, the piston will also have attained a predetermined position prior to actually reaching the fully returned initial position, in which the fluid pressure resulting from piston compression has risen to a sufficient height to act through ports 23 against forward end 48 of the valve and tend to overcome the motive fluid pressure on the rear face 70 and of the fluid against flange face 55 thereof. As the piston-compressed fluid also immediately reaches front face 57 of the internal flange 47, the fluid pressure exerted on the relatively large area thereof overcomes the effect of any fluid pressure exerted in the opposite direction on the relatively smaller area of rear face 58 of the same flange, with the result that distributing valve 37 is quickly shifted back to the position of Fig. 1, in which communication between ports 45 and rear annular groove 66 is cut off and the cycle of both piston and valve completed with both ready for a new cycle of operation. Whatever slight fluid pressure may be present in passage 53 and chamber 54 will be fully released forwardly into cylinder chamber 14 through port 51 in front of piston 11, to pass out through annular exhaust groove 15 and exhaust port 16 as indicated by the arrows in said groove and port in Fig. 1. It is to be noted that in the rearward position of valve 37, the rear face 70 of said valve engages closely against the shoulder or rear stop 71 in the valve block (Fig. 1) so that said shoulder virtually covers the rear face and initially prevents the motive fluid from impinging on said face to impart a forward impulse. Obviously, when the valve has begun to shift forwardly, the pressure fluid gains access to the rear face 70 and exerts its force thereon to serve as a holding force when this valve reaches the forward position, in the meantime assisting in the forward shifting of the valve.

In constructing the valve, care is taken to ensure that the axial distance extending from the forward end of shoulder portion 64 on the rear of valve 37 to the forward end 48 of said valve is sufficiently long to prevent the edge of rear face 65 of annular groove 66 from passing motive fluid from ports 45 while said forward end 48 exposes the shoulder or flange 30 thereto so as to allow the fluid to pass through passage 49 to ports 23. Thus only one of the ends of the valve will be effective to pass motive fluid at any given time,

and proper operation will therefore be reasonably certain.

A slight modification of the valve structure is illustrated in Figs. 3 and 4 wherein the rear portion of valve 72 and valve block 73 with its contained passages and ports include certain features departing from the corresponding valve 37 and valve block 25 of Figs. 1 and 2, the other parts and features and even the general operation being the same as in the apparatus illustrated in said first two figures, except as will now be described.

Referring particularly to Fig. 3, the piston occupies its initial rear position in cylinder chamber 13 which it is assumed just to have attained in completing a forward stroke and a rear return stroke, so that the valve 72 has been shifted to its rear position while the expanded or spent motive fluid is being released through annular exhaust groove 15 and port 16 from cylinder chamber 14.

As it is important that the forward cylinder chamber be promptly cleared of all fluid under pressure so that the subsequent forward driving stroke of the piston shall occur with maximum force, auxiliary exhausting means are called upon to serve simultaneously with the annular exhaust groove and exhaust port. To this end the erstwhile piston return passage 67 is caused to be instantly vented into an exhaust passage or port when the distributing valve is shifted from the forward position to its rear position.

Hence the valve 72 is provided with an exterior flange 74, interior flange 75, forward end 16 and rearward shoulder portion 77, and in construction and operation corresponds to valve 37 and its exterior flange 56, interior flange 47, forward end 48 and rear shoulder portion 64, respectively, in Figs. 1 and 2, cooperating with the passages and ports in valve block 73 substantially as previously described with reference to valve block 25. Between the rear annular groove 78 and the valve flange chamber 19 is a further annular exhaust groove 81 in valve block 73, connecting with the atmosphere through auxiliary exhaust port 82 (Fig. 3), said annular exhaust groove surrounding the valve 72 and being separated from annular groove 78 by a partition 83. Furthermore, the valve has an exterior annular groove forming a neck 84 upon an intermediate portion thereof separated from the rear shoulder portion 77 by means of a relatively wide and low rib 85.

Thus in the position illustrated in Fig. 3, the valve 72 cuts off communication between the passages or ports 86 and annular groove 78, but the latter, being directly connected to the return passage 67, communicates freely with the further annular exhaust groove 81 over the neck 84 on the valve past partition 83, so that the air in cylinder chamber 14 exhausts through the return passage 67, annular exhaust groove 81 and port 82 to atmosphere, simultaneously with, and also subsequently to, the escape of pressure fluid through annular exhaust groove 15 and the main exhaust port 16. The auxiliary exhaust passages 78, 81 and 82 thereby cooperate with passage 67 in preventing the compression of air by the piston near the end of its forward stroke. This feature has especial application to long-stroke machines.

When the piston 11 has travelled through the major portion of its forward driving stroke so that valve 72 is displaced to its forward position as shown in Fig. 4, the rib or flange 85 will also

have been shifted so as to register with the partition 83 which fits closely about the same and will be effective to cut off the connection between the annular groove 78 and annular exhaust groove 81. In this position the rear shoulder portion 71 of valve 72 passes motive fluid from the ports 86 and from reservoir 87 to annular groove 78 past said shoulder portion 71, and thence through piston return passage 67 to the forward cylinder chamber 14 for effecting the return stroke of the piston, after which the cycle will be repeated as long as motive fluid is supplied to valve chamber 40 of throttle valve 38. In the rearward position of valve 72, the rear holding area on end 88 is initially disposed against shoulder 89 in valve block 73 as in the case of rear end 70 on valve 37 initially engaging against shoulder 71 in valve block 25 previously described. Likewise, the relatively larger area of front face 91 and the relatively smaller area of rear face 92 on internal flange 75 function substantially as in the case of the corresponding front and rear faces 57 and 58 on flange 47 of valve 37. Thus in both forms of the valve, the internal flange serves to speed up shifting of the valve in both directions. From the foregoing it is manifest that the form and location of the distributing valve allows the same to control the flow of motive fluid to the piston automatically in both directions in effective manner and especially facilitates the flow of pressure fluid to the rear of said piston along a substantially streamlined path, while in a modified form the valve also controls auxiliary exhausting of the forward cylinder chamber to clear the path of the piston for its forward stroke.

Obviously variations may be resorted to and parts or features used without others within the scope of the invention as defined in the appended claim.

What is claimed is:

In a fluid pressure actuated rock drill comprising a cylinder having a piston reciprocable therein, a valve chest provided with a bored surface in its rear portion adapted for seating, an annular distributing valve mounted in said chest for axial reciprocation and having at its forward extremity a bored surface and adjacent its rear extremity a peripheral surface adapted to cooperate with said bored seating surface in the valve chest, a bushing coaxially disposed within the valve and spaced therefrom to provide an annular passageway therebetween

and having a peripheral surface adapted to cooperate with the bored surface of the valve, means for delivering live air constantly to the rear end of the annular passageway, a rear cylinder port or ports connecting the front end of the annular passageway with the rear end of the cylinder and adapted to be uncovered by the valve in its rearward movement, a front cylinder passage connecting the rear end of the annular passageway with the front end of the cylinder and arranged to be uncovered upon forward movement of the valve, means for applying a pressure to the valve tending to hold the valve in each of its extreme positions, and means for tripping the valve automatically in response to the movements of the piston, said tripping means comprising an internal flange on the valve extending toward said bushing, the front face of the flange having a larger area than the rear face and being in constant communication with said annular passageway whereby the resultant static pressure on the flange tends to unseat the valve when in its forward position, the inner edge of the flange being closely spaced from the bushing whereby in the rear position of the valve the impinging of air against the rear face of the flange and the reduction of pressure on the front face of the flange combine to produce a resultant of force on the flange tending to unseat the valve, said valve chest being provided with an auxiliary exhaust port connecting to the atmosphere an exhaust groove adjacent the outlet passage to the front end of the cylinder, said valve being provided adjacent its rear peripheral seat with a portion of reduced diameter or neck adapted to connect said outlet passage to the exhaust groove upon reciprocation of the valve to its rearward position whereby to provide an auxiliary exhaust passage to diminish the compression of air by the piston near the end of the forward stroke.
